CLAIM

The ornamental design for a hangable holder for small metallic objects as shown and described.

DESCRIPTION

FIG. 1 is a three-dimensional top-down view of a hangable holder for small metallic objects.

FIG. 2 is a front elevational view thereof, the rear elevational view being a mirror image thereof, therefore not shown.

FIG. 3 is a top plan view thereof.

FIG. 4 is a top plan view of the hangable holder for small metallic objects, shown in an alternate configuration of use.

FIG. 5 is a perspective bottom view of the hangable holder for small metallic objects, shown in another alternative configuration of use; and,

FIG. 6 is a perspective bottom view of the hangable holder for small metallic objects, shown in another alternative configuration of use.

The broken lines in the drawings depict portions of the hangable holder for small metallic objects that form no part of the claimed design. The unshaded surfaces shown between solid and broken lines in FIGS. 5 and 6 form no part of the claimed design.
